(57) CLAIM

The ornamental design for furniture, as shown and described.

DESCRIPTION

FIG. 1 is a perspective view of the furniture showing my new design;

FIG. 2 is a front view thereof;

FIG. 3 is a back view thereof;

FIG. 4 is a left side view thereof;

FIG. 5 is a right side view thereof; and,

FIG. 6 is a top view thereof.

In the drawings, the broken lines represent unclaimed subject matter which form no part of the claimed design.

1 Claim, 4 Drawing Sheets
